ADJUSTABLE AWNING

John D. Recob, Springfield, Ohio, assignor of one-half to Walter Ray Ross, Springfield, Ohio

Application September 6, 1949, Serial No. 114,243

3 Claims. (Cl. 20—57.5)

1

This invention relates to an awning, and one object of the invention is to provide an awning which may be adjusted to prevent the passage of bright light but permitting the free passage of air.

A further object of the invention is to provide an awning which may be adjusted to permit the unrestricted or partially restricted passage of light or to substantially prevent the passage of light.

A further object of the invention is to provide an awning of the permanently extended type having improved means to control the passage therethrough of light and air.

A further object of the invention is to provide such an awning in which the adjustment of the light and air passages is effected by the movement of a single unit.

A further object of the invention is to provide such an awning which is of a simple construction and can be easily built and installed at a relatively low cost.

Other objects of the invention may appear as the awning is described in detail.

In the accompanying drawings, Figure 1 is a perspective view of an awning embodying the invention, showing the same attached to a building; Figure 2 is a transverse section through such an awning; Figure 3 is a section taken on the line 3—3 of Figure 1; Figure 4 is a section taken on the line 4—4 of Figure 2; Figure 5 is a section taken on the line 5—5 of Figure 2.

In these drawings I have illustrated the preferred embodiment of my invention but it is to be understood that the awning as a whole, as well as the several parts thereof, may take various forms without departing from the spirit of the invention.

The awning comprises a supporting structure or frame on which are mounted two series of laterally spaced slats, the two series of slats being arranged one above the other with the slats in the two series substantially parallel one with the other. One series of the slats is movable transversely to the length of its slats with relation to the slats of the other series to move the movable slats into and out of alignment with the spaces between the slats of the other series. The two series of slats are preferably spaced vertically one from the other to provide for the free flow of air through the spaces between the slats when the movable slats are in line with the spaces between the stationary slats. The several parts of the awning may be formed from materials of any kind suitable for the purpose, and

2

the word "slat," as herein used, is intended to include any relatively narrow, elongate strip of suitable material.

In the embodiment here illustrated the supporting structure or frame comprises upper and lower horizontal frame members 10 and 11, the upper frame member 10 being rigidly secured to the wall 12 of a building above a window opening in that wall. The lower frame member 11 is spaced outwardly a substantial distance from the wall and is connected with the latter by transverse frame members 13 which are connected with the respective ends of the lower frame member 11. A series of laterally spaced slats 14 are supported at their ends by the upper and lower frame members. Preferably the several slats of the series are supported in a common plane and as herein shown the upper surfaces of the frame members 10 and 11 are flat and inclined and the ends of the slats are rigidly secured thereto. The upper and lower frame members may be mounted in such relation one to the other as to support the slats 14 at a desired inclination, and as here shown, the slats extend at an angle of approximately forty-five (45°) degrees to the vertical wall of the building.

A second series of slats, 15, are supported by the upper and lower frame members below the series of stationary slats 14 and are substantially parallel with the slats of the stationary series, and are movable transversely to their length with relation to the stationary slats to move the movable slats into and out of alignment with the spaces between the stationary slats. The movable series of slats is spaced below the upper series of slats such a distance as to permit the free flow of air through the spaces between the upper slats when the lower slats are in line with those spaces. The movable series of slats may be supported on the frame members in any suitable manner and in the present arrangement, each of the upper and lower frame members is provided with a longitudinal groove 16 which forms a guide and the ends of the movable slats are slidably mounted in these guides. Preferably the movable slats are rigidly connected one with the other for movement as a unit and as here shown the movable slats are so connected by cross bars 17. Thus the movable slats may be adjusted to positions entirely out of line with the spaces between the outer slats to provide for the unrestricted passage of light and air or to positions in which they extend partially across said spaces or to positions in which they extend entirely across said spaces so as to pre-

vent the passage of any light except that which may pass laterally between the overlapping edge portions of the upper and lower slats, and in all positions of the movable slats there is a free and substantial flow of air through the spaces between the slats.

The movable series of slats may be actuated in any suitable manner. In the present construction a toothed bar 18 is rigidly secured to an intermediate cross bar 17 and meshes with a pinion 19 carried by a shaft 20 journaled in bearings 21 and extending to a point adjacent the window opening where it may be provided with an actuating member 22. In the present instance, the shaft extends through an opening in a window screen 23, so that the awning may be adjusted from within the building.

Each side of the awning is provided with a series of vertical slats 24 spaced laterally one from the other and connected at their upper ends with the adjacent outer stationary slat and connected between their ends with cross bar 17. The slats progressively decrease in length so that the lower ends thereof may be in a straight line, or in such other arrangement as may be desired. Other vertical slats 25 extend downwardly from the lower ends of the stationary slats to approximately the level of the lower ends of the slats 24 and are rigidly connected with the lower frame member 11.

While I have shown and described one embodiment of my invention I wish it to be understood that I do not desire to be limited to the details thereof as various modifications may occur to a person skilled in the art.

Having fully described my invention, what I claim as new and desire to secure by Letters Patent, is:

1. An awning for mounting on a wall comprising; a stationary outer series of laterally spaced slats, means for supporting said slats in a common plane extending downwardly and outwardly from said wall in the direction of the length of said slats, said means including upper and lower frame members extending transversely of said slats and positioned at the longitudinal extremities of said slats, and an additional series of stationary slats depending from said outer series of laterally spaced slats around the front and side peripheral edges thereof, an inner series of laterally spaced slats extending lengthwise of said outer slats, means for mounting said inner slats entirely within said outer and additional series of slats comprising grooves in each of said frame members extending transversely of said outer slats, the ends of said inner series of slats being slidably received in said grooves, said ends lying in flush engagement with said grooves so as to allow for only sliding movement of said inner series of slats, and means for sliding said inner series of slats in said grooves in a plane parallel to and transversely of said outer slats, said last means including an actuating device mounted on said additional series of slats and operatively connected to said inner slats at a point positioned intermediately of said upper and lower frame members.

2. An awning for mounting on a wall comprising; a stationary outer series of laterally spaced slats, means for supporting said slats in a common plane extending downwardly and outwardly from said wall in the direction of the length of said slats, said means including upper and lower frame members extending transversely of said slats and positioned at the longi-

tudinal extremities of said slats, end closure means depending from said outer series of slats around the front and side peripheral edges thereof, an inner series of laterally spaced slats extending lengthwise of said outer slats, means for mounting said inner slats entirely within said outer series of slats and said end closure means, and means for sliding said inner series of slats in a plane parallel to and transversely of said outer slats, said last means including an actuating device mounted on said end closure means and operatively connected to said inner slats at a point positioned intermediately of said upper and lower frame members, said actuating device comprising a shaft extending outwardly from said wall beneath said inner slats, journal means for said shaft on said end closure means, and cooperating gear means on said shaft and inner slats for effecting movement of said slats through rotation of said shaft.

3. An awning for mounting on a wall comprising; an outer stationary series of laterally spaced slats, means for supporting said slats in a common plane extending downwardly and outwardly from said wall in the direction of the length of said slats, said means including upper and lower frame members extending transversely of said slats and positioned at the longitudinal extremities of said slats, end closure means depending from said outer series of slats around the front and side peripheral edges thereof, an inner series of laterally spaced slats extending lengthwise of said outer slats, means for mounting said inner slats entirely within said outer series of slats and said end closure means comprising grooves in each of said frame members extending transversely of said outer slats, the ends of said inner series of slats being slidably received in said grooves, said ends lying in flush engagement with said grooves so as to allow for only sliding movement of said inner series of slats, and means for sliding said inner series of slats in a plane parallel to and transversely of said outer slats, said last means including an actuating device mounted on said end closure means and operatively connected to said inner slats at a point positioned intermediately of said upper and lower frame members, said actuating device comprising a shaft extending outwardly from said wall beneath said inner slats, journal means for said shaft on said end closure means, and cooperating gear means on said shaft and inner slats for effecting movement of said slats through rotation of said shaft.
